UNITED STATES PATENT OFFICE.

LOUIS FRIEDMANN, OF VIENNA, AUSTRIA.

STEAM INJECTOR.

Application filed December 5, 1924, Serial No. 754,200, and in Austria March 26, 1924.

My invention relates to steam injectors of the type commonly used for supplying feed water to boilers and particularly locomotive boilers. This invention has for its principal object to provide a simple and efficient construction whereby the valve controlling the admission of the feed water to the injector is caused to be opened automatically whenever an amount of steam is admitted which is sufficient for the normal operation of the injector, but said feed water valve will remain closed when only a small amount of steam is admitted, for instance such as will result from leakage at the steam admission valve. With the present improvement, therefore, no water will be fed to the injector if the amount of steam is below normal requirements for the operation of the injector, and the waste of water otherwise occurring under such circumstances will be avoided.

A satisfactory and preferred embodiment of this invention is illustrated by the accompanying drawings, in which Fig. 1 is a longitudinal vertical section through such a steam injector, and Fig. 2 is a partial cross section on the line 2—2 of Fig. 1.

At 1 I have indicated the main or inner nozzle receiving steam from a conduit 1^a. This inner nozzle is surrounded by an outer nozzle 2 co-axial therewith and receiving steam through a conduit 2^a. The mixing nozzle 3 is located in advance of the outer nozzle 2 and surrounds the tip of the inner nozzle 1. The pressure nozzle 4 is arranged in advance of the mixing nozzle, the latter being surrounded by a chamber 5, in the rear of the pressure chamber 6. Water reaches the wide end of the mixing nozzle 3 from a chamber 7 which has a valve-controlled connection with the water supply at 8. Any excess water is allowed to escape from the chamber 5 through an automatically operating valve 9.

An important feature of the present invention resides in the manner of actuating the valve which controls the connection from the feed water inlet 8 to the chamber 7. This valve 12 is spring-pressed and opens toward the inlet 8. Said valve is adapted to be engaged and opened, under conditions explained hereinafter, by the stem 11 of an actuating member 10, movable in the same direction

as the valve and located within a casing 15 which it divides into two compartments 14 and 14^a respectively. Any suitable construction may be employed for the proper guiding of the valve-actuating member; for instance as indicated in Fig. 2 the said member may have a cross shaped guide member 10^a in sliding engagement with the walls of the compartment 14. The two compartments 14 and 14^a are in permanent communication with each other, in any suitable manner. The actuating member 10 therefore does not absolutely prevent the passage of steam from the compartment 14 to the compartment 14^a, as a solid piston would do. In the example illustrated permanent communication between the two compartments 14 and 14^a is established by making the actuating member 10 of sufficiently smaller diameter than the inside of casing 15, to leave a clearance all around the periphery of said member.

The compartment 14 communicates permanently with one of the steam conduits 1^a, 2^a, for instance the latter, by means of a channel 13. The compartment 14^a communicates normally with the water chamber 7 by a channel 16, through which the stem 11 of the actuating member 10 extends with a sufficient clearance to provide an ample passage for any small amount of steam flowing from the conduit 2^a through the channel 13 and through the compartments 14, 14^a past the actuating member 10, which is interposed between the channels 13, 16.

At its inner end, the channel 16 is formed with a valve seat *b*, adapted to be engaged by a corresponding valve portion *a* on the actuating member 10.

The conduits 1^a, 2^a receive steam from any suitable source. In the example illustrated, both conduits receive steam from the same source, such steam being live steam either directly from the boiler or through some intermediate connection. Steam enters an admission chamber 18 through an inlet 19, the outlet of said chamber being normally closed by the steam pressure acting against a valve 20. This valve may be opened in any suitable manner, for instance manually by means of a lever 21 operatively connected with the valve stem 22. As soon as the valve 20 is opened, steam will pass to the conduit 2^a, in sufficient volume to cause the amount which is diverted

through the channel 13 into compartments 14, 14^a and channel 16 to chamber 7, to move the actuating member 10 toward the valve 12. Upon contact of the stem 11 with said valve, 5 the latter will open, allowing water to pass from the inlet 8 to the chamber 7 and to the mixing nozzle 3, the injector being thus started with the aid of the steam reaching the outer nozzle 2 from the conduit 2^a.

10 With the valve 20 is connected so as to move in unison therewith, another valve 17, normally closing the inlet end of the steam conduit 1^a. The relative arrangement of these two valves 20, 17 is such that the valve 15 17 will not open until the valve 20 has been lifted a certain distance from its seat, so that steam will be admitted first to the conduit 2^a, to start the injector, and then to the conduit 1^a, both conduits then receiving steam 20 for the normal injector operation. At this time the actuating member 10 becomes seated on the seat *b*, thus closing the communication 25 between compartment 14^a and chamber 7.

While the valves 20, 17, are closed, the actuating member 10 is out of contact with its seat *b*. Under these circumstances, should a small amount of steam pass into the compartment 14 through the channel 13, as may occur, for instance, if there should be a leakage of steam 30 past the valve 20, such flow of steam will not be strong enough to move the actuating member 10, but will pass around the edge of said member into the compartment 14^a, and out of the latter through the channel 16 into the 35 water chamber 7. Thus, by preserving a permanent communication between the compartments 14, 14^a, I prevent the actuating member 10 and valve 12 from being operated by a slow flow of steam, and insure their being 40 operated only when intended. I thus avoid the loss of water that would result if the valve 12 were to open even upon the admission of a small amount of steam to the compartment 14. Another advantage of employing an actuating member 10 of the character described, consists in avoiding or 45 reducing the liability of such member to stick in its guides, as compared with an ordinary piston. The operation therefore becomes 50 more reliable.

Various modifications may be made without departing from the nature of my invention as set forth in the appended claims.

I claim as my invention:

55 1. In an injector, a high pressure steam nozzle and a low pressure steam nozzle, individual steam conduits leading to said nozzles, a water-supply conduit, a valve controlling the last-mentioned conduit, a casing located adjacent to said valve and having two channels, one in communication with said water conduit and the other in communication with the conduit leading to said low pressure nozzle, and an actuating member 60 mounted movably in said casing, between

said two channels and adapted to engage said valve to open the same when a sufficient amount of steam flows through the conduit for the low pressure nozzle and into said casing to establish the jet action of the injector, 70 there being a permanent communication between the two channels of the casing on opposite sides of said member, so that a moderate amount of steam may pass from said steam conduit through the casing past said member without actuating the latter. 75

2. In an injector, a high pressure steam nozzle and a low pressure steam nozzle, a steam supply conduit having a pair of branches leading one to each of said nozzles, 80 a water supply conduit, a normally closed valve for controlling the admission of water through said water conduit, a casing adjacent to said water conduit, having a restricted opening in communication with the branch conduit leading to said low pressure nozzle and in parallel with said low pressure nozzle, said casing having a second opening leading to said water conduit and an actuating member movably mounted in said casing between said two openings and adapted to engage said valve to open the same when the amount of steam owing to said low pressure nozzle through the low pressure steam branch 90 is sufficient to establish the injector jet, there 95 being a clearance space between said actuating member and said casing so that a moderate amount of steam may pass from said steam conduit through the casing past said member without actuating the latter. 100

3. In an injector, a high pressure steam nozzle and a low pressure steam nozzle, a steam conduit communicating with said low pressure steam nozzle, a water supply conduit including a casing, a water control valve mounted in said casing, a by-pass leading from said steam conduit and communicating through said casing with said water-supply conduit and a fluid pressure actuated member for opening said water control valve, said member being movably mounted in said casing in the path of the steam flow through said by-pass, and there being a sufficient clearance between said casing and member so that the latter will be actuated by said steam flow to open said valve only when enough steam is flowing to said low pressure steam nozzle to insure the establishment of the injector jet. 110

4. In an injector, a high pressure steam nozzle and a low pressure steam nozzle, individual steam supply conduits leading to said nozzles, a water-supply conduit, a normally closed admission valve controlling said water supply conduit, a casing adjacent to said admission valve having a fluid pressure actuated member movably mounted therein for opening said admission valve, the steam supply conduit for said low pressure nozzle having a pair of parallel branches, 120 125 130

one communicating with said nozzle and one with said casing, said casing being provided with an opening communicating with said water supply conduit, and a pair of manually operable valve members for admitting steam to said steam supply conduits, said valve members being so interconnected that a full

opening of the conduit leading to the low pressure nozzle and casing will be effected before steam is admitted to the high pressure ¹⁰ nozzle.

In testimony whereof I have hereunto set my hand.

LOUIS FRIEDMANN.
